SOAP CAKE

Barbara Barere, 354 Carlton Ave.,
Brooklyn, N.Y. 11238

Filed May 10, 1971, Ser. No. 142,110

Term of patent 14 years

Int. Cl. D28—02

U.S. Cl. D73—1

FIG. 1

FIG. 3

FIG. 2

FIG. 4

FIG. 5

FIG. 1 is a top plan view of a soap cake showing my new design, the bottom thereof being plain and unornamented;

FIG. 2 is a front elevational view, the back being identical thereto;

FIG. 3 is an end elevational view, the opposite end being identical thereto;

FIG. 4 is a sectional view thereof taken on the line 4—4 illustrating the central trough on the top and the facets on the upper periphery; and

FIG. 5 is a front elevational view of another embodiment of the soap cake shown in FIG. 1 wherein the top is identical in appearance to the top of the soap cake shown in FIG. 1 and the bottom thereof is identical in appearance to the top.

I claim:

The ornamental design for a soap cake, as shown and described.
